Primary Examiner — Antoine D Davis(74) *Attorney, Agent, or Firm* — Reinhart Boerner Van Deuren s.c.(57) **CLAIM**

I claim the ornamental design for a tape measure, as shown and described.

DESCRIPTION

FIG. 1 is a perspective view of a tape measure embodying the invention;

FIG. 2 is a right side view of the tape measure of FIG. 1;
FIG. 3 is a left side view of the tape measure of FIG. 1;
FIG. 4 is a front view of the tape measure of FIG. 1;
FIG. 5 is a rear view of the tape measure of FIG. 1;
FIG. 6 is a top view of the tape measure of FIG. 1; and,
FIG. 7 is a bottom view of the tape measure of FIG. 1.
